James Rood

United States Patent Office.

JAMES ROOD, OF BEAVER DAM, WISCONSIN.

Letters Patent No. 95,269, dated September 23, 1869.

IMPROVEMENT IN GRAIN-CLEANING MACHINE.

The Schedule referred to in these Letters Patent and making part of the same.

To all whom it may concern:

Be it known that I, JAMES ROOD, of Beaver Dam, in the county of Dodge, in the State of Wisconsin, have invented a new and improved Grain-Cleaner, Separator, and Grader; and I do hereby declare that the following is a full and exact description thereof, reference being had to the accompanying drawings, making a part of this specification, and to the letters of reference marked thereon, in which—

Figure 1 shows the manner of constructing the fan-arms.

Figure 2 shows the shape of the fan *c*, its manner of attachment to the arm *b*, and the position of the arm on the shaft *d*.

Figure 3 is a perspective view of the machine as encased for work.

Figure 4 is a detached view of sundry parts, arranged side by side, for the purpose of more clearly explaining the relative and co-operative positions of such parts in the machine.

Figure 5 is a detached perspective view, taken in the line *x x*, of all the working-parts of this improvement, arranged in their relative positions for work.

Similar letters of reference indicate like parts.

The object of this invention is to clean grain, and separate mixed grains and seeds, and grade wheat, all by various combinations and adjustments of the same mechanism.

To enable others skilled in the art to make and use my invention, I will proceed to describe its construction and operation.

The wooden fan-arms *b b* are halved together at right angles in the middle, and each arm-end has a bevelled slot sawed into it, as indicated at *a a a*.

The fan *c* is centred into the slot *a*, and nailed fast, as indicated in fig. 2.

By this arrangement of the fans and fan-arms, the advantage gained is, that the currents of wind flowing into the side openings of the fan-drum *A*, fig. 3, are not thrown into whirls and flurries, by reason of revolving arms constantly breaking their line of motion, as is the case when the fan-arms are attached at the ends instead of at the centre of the fan; but the two inflowing currents are struck at their point of confluence by the central-hung fan-arms, and are thus thrown forward together, while also driven by the fans in one even and powerful current. And by this central-hung and sloping position of the fans, the greatest force of wind is produced with the least expenditure of power in revolving them.

In fig. 4—

B J is the screen's drawer, and is to be drawn out at the rear of the machine.

C is a spout, which is firmly attached to the vibrator *H H*, fig. 3, and through which the No. 2

wheat is delivered at the side of the machine, thus affording the greatest convenience for pouring it back into the hopper *h*, to be run through the machine again, when desired.

D is a narrow screen, to be put in or taken out at will.

E is a sieve, coarse enough to let wheat fall through it, but pass oats over its edge into the screen's drawer, at *J*; and

f indicates a part-way bottom (made of sheet-zinc, or other suitable material,) on the sieve *E*, and upon which the wheat falls as it drops through the sieve, and is poured into the spout *C*.

F is a wide screen, and has a part-way bottom, *g*, which receives the grass-seeds, broken wheat, &c., that fall through this screen, and pours them into the screen's drawer at *J*, while the full-sized wheat is poured over the front edge of the screen on to the chute *G*, and thence upon the floor under the fan-drum *A*.

K is an index-gauged wind-board, hinged to the lower edge of the fan-drum *A*, so as to hang just above the chute *G*.

A set-screw, *i*, bearing a pointer, *j*, passes through the gauge-slot *e*, and into the end of the wind-board, so as to hold it firmly at any gauge-point desired, and the gauge-slot *e* is marked so as to indicate precisely where to set the wind-board, in order to get the best current or blast of wind for each kind of work for which the machine is adapted.

Fig. 5 shows the working-parts of this improvement in their relative and co-operative positions for work, when wheat is to be graded for No. 1 and No. 2.

The screens *D* and *F*, and the sieve *E*, rest in inclined grooves in the sides of the vibrator *H H*, fig. 3, and below the gang of sieves *L*, fig. 3. (A gang of sieves is in common use for grain-cleaning purposes, and is put in here in the usual manner.)

The process is then as follows:

The heaviest or No. 1 wheat falls from the hopper *h* down through the gang of sieves *L* upon the screen *F*, and is poured over its edge and down the chute *G*, while its screenings are poured from the part-way bottom *g* into the screen's drawer at *J*. At the same time, the lighter or No. 2 wheat and the oats are blown over the back edge of the screen *F*, so as to fall on the screen *D*, while their screenings fall upon a small chute, and thence into the screen's drawer at *B*. The wheat and oats move forward on to the sieve *E*, but the wheat sifts through on to the part-way bottom *f*, and is poured into the spout *C*, while the oats move forward over the edge of the sieve, and fall into the screen's drawer at *J*.

When it is desired not to grade wheat, but merely to clean it for market, the screen *D* is drawn out from

its place for grading, and put into the same grooves with the screen F. The wind-board being set to the proper gauge-point, all the wheat now falls on the screens F and D, adjusted together as one screen, and is poured down the chute G, the blast being now gauged so as to blow the oats over back of the screen F D, while the screenings fall into the screen's drawer at B and J, as before; but nothing falls upon the sieve E, or into the spout C, for they are entirely covered by the part-way bottom g on the screen F.

Having thus described the construction and operation of my machine, I claim as new, and desire to secure by Letters Patent—

1. The operative combination of the fans *c c c c* with the screens D and F, the sieve E, the side spout C, and the gauged wind-board K, substantially in the manner and for the purposes described.

2. The manner of constructing and arranging the sieve E and the screen F with part-way bottoms, and in combination with the detached adjustable screen D, substantially in the manner and for the purposes described.

3. The operative combination of the spout C with the screens D and F and the sieve E, substantially in the manner and for the purposes described.

4. The operative combination of the index-gauged wind-board K with the fans *c c c c*, for the purpose of gauging with uniform certainty the exact depth and elevation of wind-current for the best results in each different kind of work to be done, and substantially in the manner as described.

JAMES ROOD.
